GAS BURNER

William A. Ahern, Worcester, Mass.

Application December 15, 1931
Serial No. 581,150

8 Claims. (Cl. 158—116)

This invention relates to gas burners, and more particularly to a gas burner adapted for use in the fire boxes of domestic heating stoves, kitchen ranges, and the like.

Although many different forms of gas burners have been proposed in the past for heating and cooking purposes, these prior constructions have not in general proven satisfactory. Some of them are capable of operation only at a comparatively fixed fuel burning rate. Others are inefficient and wasteful of gas, or do not liberate the heat in the location where it can be utilized to the best advantage. Still others are complicated and expensive to manufacture and install.

It is accordingly the main object of the present invention to overcome these difficulties, and to provide a simple and inexpensive gas burner which can be readily installed in stoves or ranges, and which will produce complete combustion of the gas with the maximum liberation of heat.

It is a further object of the invention to provide a gas burner which can be operated satisfactorily at either high or low fuel burning rates, as desired.

It is a further object to provide a gas burner which can be altered readily to distribute the heat in the manner best adapted to the particular conditions encountered at installation.

With these and other objects in view, as will be apparent to those skilled in the art, my invention resides in the combination of parts set forth in the specification and covered by the claims appended hereto.

Referring to the drawing illustrating one embodiment of the invention, and in which like reference numerals indicate like parts,

Fig. 1 is a vertical section through a gas burner, the section being taken on the line 1—1 of Fig. 2;

Fig. 2 is a top plan view of the burner;

Fig. 3 is a view similar to Fig. 1, but with the burner altered to provide a different distribution of the flame; and

Fig. 4 is a view similar to Fig. 3, but with the burner altered to provide an increased fuel burning capacity.

The embodiment illustrated comprises a low base member 10 shaped to provide a small central distributing chamber 11 and an outer annular chamber 12 concentric therewith. The central chamber 11 is connected to the annular chamber 12 by means of four hollow radial arms 14, which provide passages for the flow of gas

and primary air. The member 10 may be supported in the fire box of a kitchen range or other stove in any suitable manner, and for this purpose I have shown an apertured lug 15 projecting horizontally from the outer wall of the annular chamber 12.

A boss 16 projects downwardly from the lower wall of the central chamber 11, and this boss is provided with an internally threaded opening to receive the upper end of a vertical Venturi tube 18 which serves as a gas and air mixing device. Gas is introduced axially into the lower end of the tube 18 by means of a gas inlet nozzle 19 to which a gas supply pipe 20 is connected. Primary air enters the lower end of the tube 18 through air inlet orifices 22 surrounding the gas nozzle 19. These air orifices 22 may be adjusted in size by means of a shutter 23, whereby the proportions of air and gas entering the mixing tube 18 may be controlled. It will be understood that the supply of gas may be varied by means of a suitable valve (not shown) in the pipe 20. The gas in entering the tube 18 produces an aspirating effect which draws into the tube the proper quantity of air through the openings 22, and the mixture of air and gas flows upwardly to the central chamber 11 and thence outwardly through the radial passages 14 to the annular chamber 12.

In order to provide a large gas burning capacity and an extensive incandescent surface for the transmission of radiant heat to the heat absorbing surfaces, such as the water back of a kitchen range, I have shown an outer cylindrical shell 25 and an inner cylindrical shell 26, mounted above and concentric with the annular chamber 12. These parts are so arranged that gas and air are discharged upwardly from the chamber 12 into the annular space 27 between the shells. In order that the mixture of gas and air may escape from the space 27 and burn, I provide a large number of small openings or perforations 29 in the shell 25 and a large number of small openings or perforations 30 in the shell 26. The shells are of considerable height, preferably at least three or four inches, and the gas exit openings are located over substantially the entire area of the shells. An annular sealing cap 31 is provided at the top of the shells to prevent the gas from escaping upwardly from the space 27 and to insure an adequate pressure within this space. The total area of the openings 29 and 30 is so proportioned to the quantity of gas to be burned that in normal operation a sufficient pressure is always maintained in the

annular space 27 to insure discharge of gas and air through all the openings. These openings are all effective for gas discharge, so that heat is produced low in the fire box where it may be 5 readily absorbed by the water back. The shells 25 and 26, and the cap 31 are preferably comparatively thin and formed of a suitable heat resisting material, such as chrome steel, which can be maintained at a high temperature for 10 the rapid radiation of heat.

It will be understood that when the burner is in operation, secondary air will flow upwardly around the outside of the shell to mingle with the ignited gas jets issuing from the openings 15 29, and additional secondary air will flow upwardly between the radial arms 14 to mingle with the ignited gas jets issuing from the openings 30. This secondary air serves to complete the combustion of the gas and provide an intense heat. I have found that the operation 20 may be improved by providing a cylinder 33 to act as a baffle and compel the secondary air to travel close to the burning gas. This cylinder 33 is somewhat smaller in diameter than the shell 26 and is mounted concentric therewith. It is preferably formed of the same material as the shells, and it may be supported by means of an annular flange 34 projecting upwardly from the upper wall of the central chamber 11. 25 With this construction, the cylinder 33 and the inner shell 26 provide an annular passage which is open at the top. The base member 10 provides openings between the radial arms 14, and these openings communicate with the annular 30 passage so that secondary air may flow upwardly therethrough.

When the supply of gas is reduced, the velocity of the gas and air passing through the openings 29 and 30 will decrease. As soon as this velocity 40 becomes less than the rate of flame propagation in the mixture, there will be a tendency for the flame to strike back inside the burner and ignite the gas at the nozzle 19. In order to overcome this difficulty and allow satisfactory operation at low fuel burning rates, I provide a flat 45 annular plate 36 directly above the annular chamber 12. This plate 36 is provided with orifices 37 having a total area considerably less than the combined area of the openings 29 and 50 30. The velocity of flow through the orifices 37 will exceed the rate of flame propagation even when the burner is operating at a low capacity, and striking back of the flame will be prevented.

At certain times it may be desirable to 55 concentrate the heat above the burners, and to reduce the quantity of heat radiated laterally therefrom. This may be accomplished by replacing the outer shell 25 with an imperforate shell or cylinder 39, as shown in Fig. 3. The 60 parts 25 and 39 are made interchangeable, and the burner is so arranged that one part may be readily removed and the other slipped on in its place. If desired, the sealing cap 31 may be replaced with a similar cap 40 having orifices 41 65 therein to provide upwardly directed jets of flame.

In case still further concentration of heat is 70 desired above the burner, the imperforate cylindrical baffle 33 may be replaced by a cylinder 43 having a number of small openings or perforations 44 therein, as shown in Fig. 4. A circular cap 45 is provided to close the top of the cylinder 43, and this cap may have orifices 47 therein. 75 Gas and primary air enter the cylinder 43 through an opening 48 in the upper wall of the

central chamber 11. This opening may be closed by a plug 49, as shown in Fig. 1, when the baffle 33 is in use. The opening 48 is preferably considerably less in area than the total areas of the orifices 44 and 47, to prevent striking back 80 of the flame.

The operation of the invention will now be clear from the above disclosure. Gas is supplied to the nozzle 19 at a desired rate through the pipe 20, and primary air enters through the orifices 22 and is mixed with the gas in the Venturi tube 18. The mixture flows upwardly to the chamber 11, thence radially through the passages 14 to the annular chamber 12, upwardly through the orifices 37 to the space 27, and outwardly through the openings 29 and 30, where it is ignited. The plate 36 prevents the flame from striking back inside the burner. Secondary air flows upwardly past the burning jets and completes the combustion of the gas. 90 The cylinder 33 forces the secondary air to travel through the flame, and draws the flame and heat in to the center of the burner at the top, thereby concentrating the heat at the center of a dish when the stove cover is removed. 95

The outer shell 25 provides an extensive incandescent surface which transmits heat by radiation directly to the water back of the range in which the burner is installed. Since primary air is mixed with the gas in the tube 18, the 100 openings 29 are all effective as gas and air discharge orifices, and the burner provides heat well down in the fire box for the heating of water. If it is desired to dispense with the water heating at certain seasons of the year, or if there is no water back in the range, the burner 105 can be easily changed to the arrangement shown in Fig. 3, which will give very little lateral radiation of heat. In case very high fuel burning capacities are desired, without heating the water back, the arrangement shown in Fig. 4 is desirable. It will thus be seen that I have provided a gas burner which is not only simply constructed and efficient, but also may be readily altered to meet varying conditions of use. 110

Having thus described my invention, what I 115 claim as new and desire to secure by Letters Patent is:

1. A gas burner comprising a base member shaped to provide an annular chamber, a pair 120 of concentric cylindrical shells mounted above the chamber, the annular space between the shells communicating with the chamber, and the inner shell having openings therein for the escape of gas from the annular space, means to 125 introduce gas into the annular chamber, and an annular cap mounted at the top of the shells so that a sufficient pressure may be maintained in the annular space to force the gas outwardly 130 therefrom through the openings, the inner shell 135 serving as the outer wall of a passage which is open at the top and the base member being shaped to provide an opening communicating with said passage, whereby air may flow upwardly through the passage and past the issuing 140 gas jets.

2. A gas burner comprising a base member shaped to provide an annular chamber, a pair 145 of concentric thin perforated cylindrical shells mounted above the chamber with the annular space between the shells in direct communication with the chamber, means to introduce gas into the annular chamber, and an annular cap mounted at the top of the shells so that a sufficient pressure may be maintained in the an- 150

- nular space to force the gas outwardly therefrom through the perforations in both the shells, the inner shell serving as the outer wall of a passage which is open at the top and the base member being shaped to provide an opening communicating with said passage, whereby air may flow upwardly through the passage and past the gas jets issuing from the perforations in the inner shell. 80
- 10 3. A gas burner comprising a base member shaped to provide an annular chamber, a pair of concentric thin cylindrical shells of considerable height mounted above the chamber with the annular space between the shells in direct communication with the chamber, both the shells being provided with small closely spaced openings throughout substantially their entire area, means to introduce a mixture of gas and primary air into the annular chamber, and an annular cap mounted at the top of the shells so that a sufficient pressure may be maintained in the annular space to force the gas and primary air outwardly therefrom through all the openings in both the shells, the inner shell serving as the outer wall of a passage which is open at the top and the base member being shaped to provide an opening communicating with said passage, whereby secondary air may flow upwardly through the passage to complete the combustion of the gas issuing into said passage. 90
- 15 4. A gas burner comprising a base member shaped to provide an annular chamber, a pair of concentric cylindrical shells mounted above the chamber with the annular space between the shells in direct communication with the chamber, the inner shell being perforated, means to introduce a mixture of gas and primary air into the annular chamber, and an annular cap mounted at the top of the shells so that a sufficient pressure may be maintained in the annular space to force the gas and primary air outwardly therefrom through the perforations in the inner shell, the inner shell serving as the outer wall of a passage which is open at the top and the base member being shaped to provide an opening communicating with said passage, whereby secondary air may flow upwardly through the passage to complete the combustion of the gas, the perforated annular plate serving to bring about a localized increase in the velocity of the mixture of gas and primary air and thus prevent striking back of the flame. 100
- 20 5. A gas burner comprising a base member shaped to provide an annular chamber, a pair of concentric cylindrical shells mounted above the chamber with the annular space between the shells in direct communication with the chamber, the inner shell being perforated, means to introduce a mixture of gas and primary air into the annular chamber, and an annular cap mounted at the top of the shells so that a sufficient pressure may be maintained in the annular space to force the gas and primary air outwardly therefrom through the perforations in the inner shell, the inner shell serving as the outer wall of a passage which is open at the top and the base member being shaped to provide an opening communicating with said passage, whereby secondary air may flow upwardly through the passage to complete the combustion of the gas. 110
- 25 6. A gas burner comprising a base member shaped to provide a central distributing chamber, an outer annular chamber concentric therewith, and hollow radial arms providing passages leading from the distributing chamber to the annular chamber, a pair of concentric cylindrical shells mounted above the annular chamber with the annular space between the shells in direct communication therewith, the inner shell being perforated, a perforated cylinder concentric with and smaller in diameter than the inner shell, the space within the cylinder communicating directly with the distributing chamber, means to introduce a mixture of gas and primary air into the distributing chamber, a circular cap mounted on top of the cylinder, and an annular cap mounted at the top of the shells, whereby a sufficient pressure may be maintained in the space within the cylinder and the annular space between the shells to force gas outwardly therefrom through the perforations in the cylinder and the inner shell, the cylinder and inner shell forming an annular passage which is open at the top, and the parts being so constructed and arranged that secondary air may flow upwardly between the radial arms and thence into the said annular passage to complete the combustion of the gas. 120
- 30 7. A gas burner comprising a base member shaped to provide a central distributing chamber, an outer annular chamber concentric therewith, and hollow radial arms providing passages leading from the distributing chamber to the annular chamber, a pair of concentric cylindrical shells mounted above the annular chamber with the annular space between the shells in direct communication therewith, the inner shell being perforated, means to introduce a mixture of gas and primary air into the distributing chamber, a circular cap mounted on top of the cylinder, and an annular cap mounted at the top of the shells, whereby a sufficient pressure may be maintained in the space within the cylinder and the annular space between the shells to force gas outwardly therefrom through the perforations in the cylinder and the inner shell, the cylinder and inner shell forming an annular passage which is open at the top, and the parts being so constructed and arranged that secondary air may flow upwardly between the radial arms and thence into the said annular passage to complete the combustion of the gas. 130
- 35 8. A gas burner comprising a base member shaped to provide a central distributing chamber, an outer annular chamber concentric therewith, and hollow radial arms providing passages leading from the distributing chamber to the annular chamber, a pair of concentric cylindrical shells mounted above the annular chamber with the annular space between the shells in direct communication therewith, the inner shell being perforated, a perforated cylinder concentric with and smaller in diameter than the inner shell, the space within the cylinder communicating directly with the distributing chamber, means to introduce a mixture of gas and primary air into the distributing chamber, a circular cap mounted on top of the cylinder, and an annular cap mounted at the top of the shells, whereby a sufficient pressure may be maintained in the space within the cylinder and the annular space between the shells to force gas outwardly therefrom through the perforations in the cylinder and the inner shell, the cylinder and inner shell forming an annular passage which is open at the top, and the parts being so constructed and arranged that secondary air may flow upwardly between the radial arms and thence into the said annular passage to complete the combustion of the gas. 140
- 40 9. A gas burner comprising a base member shaped to provide a central distributing chamber, an outer annular chamber concentric therewith, and hollow radial arms providing passages leading from the distributing chamber to the annular chamber, a pair of concentric cylindrical shells mounted above the annular chamber with the annular space between the shells in direct communication therewith, the inner shell being perforated, a perforated cylinder concentric with and smaller in diameter than the inner shell, the space within the cylinder communicating directly with the distributing chamber, means to introduce a mixture of gas and primary air into the distributing chamber, a circular cap mounted on top of the cylinder, and an annular cap mounted at the top of the shells, whereby a sufficient pressure may be maintained in the space within the cylinder and the annular space between the shells to force gas outwardly therefrom through the perforations in the cylinder and the inner shell, the cylinder and inner shell forming an annular passage which is open at the top, and the parts being so constructed and arranged that secondary air may flow upwardly between the radial arms and thence into the said annular passage to complete the combustion of the gas. 150
